(57) **CLAIM**

The ornamental design for an automobile and/or toy replica thereof, as shown and described.

DESCRIPTION

FIG. 1 is a left front perspective view of an automobile and/or toy replica thereof of our new design;

FIG. 2 is a front view thereof, the rear view being a mirror image thereof, with the exception of the fuel door which is not present on the rear view;

FIG. 3 is a right front perspective view thereof;

FIG. 4 is a left side view thereof;

FIG. 5 is a right side view thereof; and,

FIG. 6 is a top plan view thereof.

The bottom view of the automobile and toy replica forms no part of the claimed design.
